UNITED STATES PATENT OFFICE.

HARRY BARKBY, OF NEW CASTLE, PENNSYLVANIA, ASSIGNOR TO WARWICK CHINA COMPANY, OF WHEELING, WEST VIRGINIA.

DESIGN FOR A PLATE OR SIMILAR ARTICLE.

Application filed January 3, 1928. Serial No. 24,739. Term of patent 7 years.

To all whom it may concern:

Be it known that I, HARRY BARKBY, a citizen of Great Britain, residing at New Castle, in the county of Lawrence and State of Pennsylvania, have invented a new, original, and ornamental Design for a Plate or Similar Article, of which the following is a specification, reference being had to the accompanying drawings, forming part thereof. The design illustrated is continued throughout the border of the article.

The figure is a plan view of the plate, showing my new design.

I claim:

The ornamental design for a plate or similar article as shown and described.

HARRY BARKBY.
